COMBINATION HEATING AND COOLING
UNIT

Frederick S. Baird and Carl H. Marsh, Ada, Okla.

Application February 10, 1936, Serial No. 63,223

3 Claims. (Cl. 126—116)

The invention relates to a combination heating and cooling unit.

The primary object of the invention is the provision of a unit of this character, wherein 5 the heated air will be properly humidified for the purpose of heating a room or rooms of a building and particularly where such building lacks a cellar or a furnace room, the unit being of novel construction and is readily convertible 10 for cooling purposes.

Another object of the invention is the provision of a unit of this character, wherein the same is susceptible of being suspended from the floor within a building for installation where such 15 building lacks a cellar or basement or what is more commonly known as a furnace room and the unit when operating functions as a heater as well as a cooling unit. The air heated is susceptible of treatment to eliminate dryness so 20 that the heated air will be thoroughly humidified and the heating of the building or room being successfully carried forth without regard to the size of the same.

A further object of the invention is the provision of a unit of this character, which is comparatively simple in its construction, thoroughly reliable and effective in its operation, enabling 25 the installation economically, durable, affording a combination heater and cooler and inexpensive to manufacture and install.

With these and other objects in view, the invention consists in the features of construction, combination and arrangement of parts as will be hereinafter more fully described, illustrated 30 in the accompanying drawings, which disclose the preferred embodiment of the invention and pointed out in the claims hereunto appended.

In the accompanying drawings:

Figure 1 is a top plan view partly in section 40 of a heater constructed in accordance with the invention.

Figure 2 is a sectional view on the line 2—2 of Figure 1.

Figure 3 is a sectional view on the line 3—3 of 45 Figure 2.

Figure 4 is a sectional view on the line 4—4 of Figure 2.

Similar reference characters indicate corresponding parts throughout the several views in 50 the drawings.

Referring to the drawings in detail, A designates generally a portion of a flooring within an edifice, as for example, a building devoid of a basement or cellar and this flooring is cut away 55 sufficiently for the installation of a heating and

cooling unit constructed in accordance with the invention and hereinafter fully described.

The unit constituting the present invention comprises a substantially rectangular shaped body 10 preferably made from sheet metal and 5 has interiorly thereof separated twin fire boxes 11 having common thereto a hood formation 12. The body 10 at its top is formed with a marginal lateral flange 13 counterseated in the top face of the floor A at the opening or cut away 10 portion for said unit so that it will be suspended beneath said floor in operative position.

The fire boxes 11 are spaced from each other and about the hood 12 is a heat distributing wall 14 preferably made from insulating material and providing between it and the hood an air outlet space or chamber 15 for directing air heated in an upward direction through a register plate 16 carried at the top of the unit.

The fire boxes 11 at the upper portion of the 20 hood have communication with circuitous flues 17, these being located between the boxes and open into an outlet nipple or opening 18 to a discharge chimney or flue so that the spent products of combustion will be delivered from the unit 25 thereto.

Between the body 10 and the wall 14 is an air inlet chamber or space 19 leading to a downwardly tapered lower end portion 20 built with the said unit, the air being admitted in a downward direction through the register plate 16 to the chamber or space 19 for the heating thereof within the body 10. The wall 14 is continued into the lower portion 20 and inwardly angled at 21 which angled portion is provided with louvered 30 openings 22 communicative with fan chambers 23, these being separated by partitions 23' and cross webs 23'', respectively. In each of the chambers 23 is arranged an electric fan 24 the electric circuit thereof being controlled by a 35 switch 25. The fan is operated for cooling when the unit is utilized as a cooling unit.

Located within each fire box 11 is a gas burner 26, its feed pipe 27 being fitted with a valve 28 controlled by a turn key 29 accessible at the top 40 of the unit for regulating or shutting off the supply through the pipe 27 to the burner 26. Co-active with the burner 26 is a lighting pilot 30 equipped with a valve 31.

Arranged within the chamber 19 is a water spray tube 32, its water feed line being indicated at 33 equipped with a valve 34 and this tube 32 when spraying water within the chamber 19 enables the humidifying of the heated air.

It is preferable to have the hood 12 formed 55

with peep openings 35, these covered by heat resisting transparent panels 36 which are removable to permit convenient lighting of the pilots 30 associated with both burners 26.

5 The hopper portions 20 have leading therefrom at the lowermost points thereof drain pipes 37 for the discharge of the water from the tube 32.

In the suspended position of the unit from the floor A the heated air will be delivered through 10 the register plate 16 interiorly of a room or building and such heated air is humidified, the burners 26 heating the air.

When it is desired to use the unit as an air conditioning or cooling unit the fans 24 are 15 started so that this air under the force of the fan will be circulated through the register plate 16 into the room or building. This circulated air will be water sprayed for air cooling effect.

The circuitous flues deliver the spent products 20 of combustion within the fire boxes to the opening 18 which is located at the transverse center of the body of the unit and intermediate of the fire boxes interiorly thereof.

The fire boxes have the lateral housings 38, 25 these opening through opposite ends of the body as will be apparent from Figure 2 of the drawings. Located between the twin fire boxes 11 at the hood common thereto and the wall 14 are braces 39, these being located preferably at the four 30 corners of said hood and sustained in spaced relation between the hood and said wall 14.

What is claimed is:

1. A unit of the character described comprising a casing having a grated top and a downwardly tapered lower end, separated twin fire boxes interiorly of said casing, a wall about said fire boxes and spaced from the casing and also said fire boxes to effect air inlet and outlet spaces through said grated top, the wall being extended 40 into the tapered lower end of said casing and inwardly angled at its lower portion, the angled areas of said wall being formed with windows, partitions and webbings arranged within the said wall and constituting therewith fan chambers 45 beneath the fire boxes, fans operating within said chambers, the louvered windows establishing communication between the chambers and the air inlet space, a water spray located in the air inlet space between the casing and said wall, 50 and lateral housings formed with the fire boxes and opening reversely to each other through

opposite sides of said casing and carried through said wall.

2. A unit of the character described comprising a casing having a grated top and a downwardly tapered lower end, separated twin fire boxes interiorly of said casing, a wall about said fire boxes and spaced from the casing and also said fire boxes to effect air inlet and outlet spaces through said grated top, the wall being extended into the tapered lower end of said casing and 10 inwardly angled at its lower portion, the angled areas of said wall being formed with windows, partitions and webbings arranged within the said wall and constituting fan chambers beneath the fire boxes, fans operating within 15 said chambers, the louvered windows establishing communication between the chambers and the air inlet space, a water spray located in the air inlet space between the casing and said wall, lateral housings formed with the fire boxes and 20 opening reversely to each other through opposite sides of said casing and carried through said wall, and a hood common to the fire boxes and establishing communication therebetween.

3. A unit of the character described comprising a casing having a grated top and a downwardly tapered lower end, separated twin fire boxes interiorly of said casing, a wall about said fire boxes and spaced from the casing and also said fire boxes to effect air inlet and outlet spaces through said grated top, the wall being extended into the tapered lower end of said casing and 25 inwardly angled at its lower portion, the angled areas of said wall being formed with windows, partitions and webbings arranged within the said wall and constituting fan chambers beneath the fire boxes, fans operating within 30 said chambers, the louvered windows establishing communication between the chambers and the air inlet space, a water spray located in the air 35 inlet space between the casing and said wall, lateral housings formed with the fire boxes and opening reversely to each other through opposite sides of said casing and carried through said wall, a hood common to the fire boxes and establishing communication therebetween, and burners 40 arranged within said housings for effecting combustion in said fire boxes and accessible through the open ends of said housings.
